US0D1105320S

(12) **United States Design Patent** (10) **Patent No.:** **US D1,105,320 S**
(45) **Date of Patent:** **** Dec. 9, 2025**

(54) **BALL**

(71) Applicant: **adidas AG**, Herzogenaurach (DE)

(72) Inventor: **Franziska-Maria Eva Löffelmann**,
Behringersdorf (DE)

(73) Assignee: **adidas AG**, Herzogenaurach (DE)

(**) Term: **15 Years**

(21) Appl. No.: **29/912,281**

(22) Filed: **Sep. 15, 2023**

(30) **Foreign Application Priority Data**

Mar. 17, 2023 (EM) 015014861-0001

(57) **CLAIM**

The ornamental design for a ball as shown and described.

DESCRIPTION

FIG. 1 is a perspective view of a ball showing the claimed design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a bottom plan view thereof; and,

FIG. 7 is a top plan view thereof.

The figures show the claimed design in grayscale. No specific gray coloring is claimed.

1 Claim, 7 Drawing Sheets
